APPARATUS FOR EXTRACTING DRUGS
AND THE LIKE

Heinrich Breddin, Kirchhain, Germany

Application April 4, 1934, Serial No. 719,047
In Germany October 21, 1932

6 Claims. (Cl. 87—28)

The invention relates to apparatus for extracting drugs and the like in accordance with the method, in which the extraction fluid is slowly forced through one or several tubular vessels connected one behind the other, which vessels are filled with the comminuted drugs, so that the advance particles of fluid may enrich themselves to a very high degree with the extract substances whilst the portions of the extraction fluid, which flow through later, and which are displaced by another neutral fluid, absorb the originally remaining extract substances until the drugs are exhausted almost completely.

The object of the invention is an apparatus designed for efficiently carrying out this extraction process, which enables given quantities of drugs to be lixiviated with relatively small quantities of extraction fluid and makes possible the direct recovery of highly concentrated extracts, 20 at the same time avoiding the disadvantages of inspissating or drying by evaporation.

The essentially novel feature of the apparatus consists in that the more or less large number of extraction tubes, which serve to receive the 25 drugs to be extracted and which are linked up by intermediate tubular members, are connected up to a storage vessel which is associated with devices for putting same under pressure, and in providing special auxiliary means which are 30 interposed in a tubular connection between said vessel and the extraction tubes and which permit a very slow influx of the extraction and displacement fluid to the extraction tubes. The speed of flow is accurately controlled and the 35 exceedingly high resistance to flow, of which the delivery of fluid is made independent, is also overcome.

The invention will be better understood by reference to the accompanying drawing in which 40 Figure 1 shows an extraction apparatus constructed in accordance with the invention partly in elevation and partly in vertical section.

Fig. 2 is a sectional view upon an enlarged scale taken longitudinally through the blow-off valve of 45 the device.

Fig. 3 shows, upon an enlarged scale, a cross-section through the throttle device on line III—III of Fig. 1.

Fig. 4 is a large-scale vertical section of the check valve,

Fig. 5 a view of same from below.

Fig. 6 is a front elevation of an auxiliary device for attaching the combined float and visible 55 drip feed chambers to the first extraction tube,

Fig. 7 is a plan view of the attaching device.

The storage vessel 1, serves to receive the quantity of extraction fluid required for the operation and the displacement fluid necessary for expelling it from the extraction tubes. This vessel 1 takes the form for example, of a pressure-proof tightly sealable glass vessel. The sealing plug 2 of this vessel is traversed by an ascension pipe 3 reaching almost to its bottom and a tubular branch 4 which, underneath its upper tight connection with the body of the tube 3, has two lateral branch pipes 5, 6 of which the one is connected to a pneumatic pressure pump, comprising for example, a hand operated bulb 7 provided with pressure and suction valves, whilst the other one is connected to a pressure gauge 8.

An adjustable throttle device serving to control the speed of flow is attached to the top of the ascension pipe 3, and consists preferably of a short piece of rubber tubing 9, which is provided with a filling 10 consisting of a piece of wick or a loose bundle of fibres and lies between the two pressure plates 11, 12 of a pinch-cock, so that by means of the pressure screw of same, the wick filling 10 may be more or less compressed. The upper end of the tubing 9, of the throttle device is connected through a bend 13 to a lateral nipple 14 of a float chamber 15 in the form of a vertical glass tube. This chamber contains a float 16, which in the raised position shuts off the lower inlet opening of the tube 17, arranged at the upper end of the float chamber.

The bottom end of the float chamber terminates in a downwardly directed tube 18, which protrudes into a sight-feed or visible drip chamber 19, consisting of a further piece of transparent glass tubing, the said tube 18, passing through a sealing stopper at the top of the chamber. At the bottom end of this drip tube 18 there is a check valve 20, which only allows egress from the tube 18 into the visible drip chamber but prevents passage in the reverse direction. The check valve is preferably of soft rubber after the manner of the well-known lip valve, which consists of a connecting sleeve with a flattened-off outlet orifice 21 adjoining same.

The bottom tube 22 of the visible drip chamber 19 is joined by a union 23 to the bend 25 forming the bottom connection to the first extraction tube 24. The other end of the extraction tube is joined up to the next extraction tube 26 by an intermediate tube 27 leading to the bottom end of same. Any number of extraction tubes may be used and each connected with the preceding one by an

intermediate tube. The last of these extraction tubes terminates in an outlet 28 in the form of a double bend under whose bottom orifice is the collecting vessel 29. The object of the float valve 16 is merely to close the exhaust tube 17, as long as liquid is forced from the supply tank through the float chamber 15. If, after exhausting the supply of liquid, compressed air instead of the liquid passes into the float chamber from the supply tank, so that the liquid in the float chamber is gradually expelled through the back pressure valve 20, the float will sink and thereby open the lower aperture of the exhaust tube 17. Through the latter, the air still present in the supply vessel 15 and under a certain pressure will escape into the open air. Also the air contained in the auxiliary chamber 19 is under the hydraulic excess pressure of the column of liquid filling the tubes 24, 26 and the intermediate tube 27. It may happen that in one of these tubes or containers air cushion ions are enclosed which, after the actuating air pressure in the supply tank 1 is exhausted may expand backward and may, just as the hydraulic pressure does, drive liquid from the neighboring extraction tube 24 back into the auxiliary chamber 19. The object of the back pressure valve 20 is to prevent by such action the passage of the quantity of air contained in the auxiliary chamber into the open air through the float chamber 15. The retention of the air normally contained in the auxiliary chamber by means of the back pressure valve is necessary in order to be able to notice the falling of the drops.

The double tubular member formed of the combined float chamber 15 and the visible drip chamber 19 may, in this form, be advantageously attached to the body of the first extraction tube 24, which, like the remaining portions of the apparatus, is detachably mounted on a suitable frame or stand.

The attachment of the double tubular member may be effected by means of an intermediate mounting member 30 consisting of a block of wood or the like and having one side face formed with a longitudinal channel 31 in which rests the body of the extraction tube 24. This mounting member has its opposite side face formed with a similar longitudinal channel 31 which is parallel with the first one and in which fit the combined tubular body of the visible drip chamber and float chamber. The parts are preferably secured by elastic bands which are attached to the block by fasteners 34 and are drawn round the three glass bodies and have their ends detachably secured to each other by means of buttons and button holes 35.

I claim:

1. In an apparatus of the character described, a vertically disposed extraction chamber having an outlet at its top and an inlet at its bottom, a liquid supply vessel, a discharge tube leading upwardly from said vessel and having its lower end adjacent the bottom of the vessel, means for supplying compressed air to the upper portion of said vessel for forcing liquid therefrom through said tube, an auxiliary chamber disposed vertically adjacent one side of the extraction chamber and having its lower end communicating with the lower end of the extraction chamber, a delivery chamber disposed vertically above the auxiliary chamber and having a discharge nozzle extending from its bottom down into the auxiliary chamber, said tube communicating with the delivery chamber in spaced relation to its lower end, said delivery chamber having an outlet at

its upper end, means in said delivery chamber responsive to the level of liquid in the delivery chamber for controlling flow of air through the air outlet, and means carried by the lower end of said nozzle for retarding the liquid and effecting a drop by drop delivery of liquid from the nozzle of the delivery chamber into the auxiliary chamber. 5

2. In an apparatus of the character described, a cylindrical vertically disposed extraction chamber having an outlet at its top and an inlet at its bottom, a liquid supply vessel, a discharge tube extending upwardly from said vessel and having its lower end adjacent the bottom of the vessel, means for supplying compressed air to the upper portion of said vessel for forcing liquid through the tube, an auxiliary chamber disposed vertically adjacent one side of the extraction chamber and having its lower end communicating with the inlet at the lower end of the extraction chamber, a delivery chamber disposed vertically above the auxiliary chamber and having an air outlet at its upper end, a discharge nozzle extending from the lower end of said delivery chamber down into the upper end of the auxiliary chamber, said tube communicating with the delivery chamber in spaced relation to the lower end thereof, means responsive to the level of liquid in the delivery chamber for controlling flow of air through the air outlet, an intermediate portion of said tube being formed of compressible material, a filling of fibrous material in the flexible tube section, a clamp about the flexible tube section having a stationary jaw and a movable jaw engaging the flexible tube section from opposite sides, means for forcing the movable jaw towards the stationary jaw to compress the flexible tube section and filling and regulating flow of liquid through the tube into the delivery chamber, and means carried by the nozzle for retarding flow of liquid and effecting a drop by drop delivery of liquid from the nozzle of the delivery chamber into the auxiliary chamber. 30

3. In an apparatus of the character described, a cylindrical vertically disposed extraction chamber having an outlet at its top and an inlet at its bottom, a liquid supply vessel, a discharge tube extending upwardly from said vessel and having its lower end adjacent the bottom of the vessel, means for supplying compressed air to the upper portion of said vessel for forcing liquid through the tube, an auxiliary chamber disposed vertically adjacent one side of said extraction chamber and having its lower end communicating with the inlet at the lower end of the extraction chamber, a delivery chamber disposed vertically above the auxiliary chamber and having an air outlet at its upper end, a discharge nozzle extending from the bottom of said delivery chamber down into the upper end of the auxiliary chamber, said tube communicating with the delivery chamber in spaced relation to the bottom thereof, means controlled by level of liquid in the delivery chamber for controlling flow of air through the air outlet, means for controlling flow of liquid through the tube into the delivery chamber, and means carried by the lower end of the nozzle for retarding flow of liquid and effecting a drop by drop delivery of liquid from the nozzle into the auxiliary chamber. 55

4. In an apparatus of the character described, a cylindrical vertically disposed extraction chamber having an outlet at its top and an inlet at its bottom, a liquid supply vessel, a discharge tube extending upwardly from said vessel and

having its lower end adjacent the bottom of the vessel, means for supplying compressed air to the upper portion of said vessel, for forcing liquid through the tube, an auxiliary chamber disposed vertically adjacent one side of said extraction chamber and having its lower end communicating with the inlet at the lower end of the extraction chamber, a delivery chamber disposed vertically above the auxiliary chamber and having an air outlet at its top, a discharge nozzle extending from the bottom of said delivery chamber down into the upper end of the auxiliary chamber, said tube communicating with the delivery chamber in spaced relation to the bottom thereof, means for controlling flow of liquid through the tube into the delivery chamber, a float in said delivery chamber movable vertically therein from a position for closing the air outlet to a lowered position for opening the air outlet, and an elastic nipple fitting about the lower end of said nozzle with its lower portion projecting from the nozzle and flattened to retard flow of liquid from the nozzle and cut to provide a diagonally extending lower edge from which liquid will be delivered drop by drop from the nozzle into the auxiliary chamber.

5. In an apparatus of the character described, a cylindrical vertically disposed extraction chamber having an outlet at its top and an inlet at its bottom, a liquid supply vessel, a discharge tube extending upwardly from said vessel and having its lower end adjacent the bottom of the vessel, means for supplying compressed air to the upper portion of said vessel for forcing liquid through the tube, an auxiliary chamber disposed vertically in spaced relation to one side of said extraction chamber and having its lower end communicating with the inlet at the lower end of the extraction chamber, a delivery chamber disposed vertically above the auxiliary chamber and having an air outlet at its upper end and a dis-

charge nozzle extending from its lower end into the upper end of the auxiliary chamber, a float valve in the delivery chamber for controlling flow of air through the outlet, a block extending vertically between the extraction chamber and the auxiliary chamber and delivery chamber, securing means carried by said block and engaged about said chambers, said tube communicating with the auxiliary chamber above the lower end thereof, and means carried by the nozzle for retarding flow of liquid through the nozzle and effecting a drop by drop delivery of liquid from the nozzle into the auxiliary chamber.

6. In an apparatus of the character described, a cylindrical vertically disposed extraction chamber having an outlet at its top and an inlet at its bottom, a liquid supply vessel, a discharge tube extending upwardly from said vessel and having its lower end adjacent the bottom of the vessel, means for supplying compressed air to the upper portion of said vessel for forcing liquid through the tube, an auxiliary chamber disposed vertically adjacent one side of the extraction chamber and having its lower end communicating with the inlet at the lower end of the extraction chamber, a delivery chamber disposed vertically above said auxiliary chamber, a nozzle extending from the lower end of the delivery chamber into the upper end of the auxiliary chamber, said delivery chamber being provided with an air outlet at its top, said tube communicating with the delivery chamber above its lower end, a float valve in the delivery chamber movable upwardly therein to a position for closing the air outlet and movable downwardly as liquid is exhausted from the supply chamber to uncover the air outlet and close the nozzle, and means carried by the nozzle for retarding flow of liquid through the nozzle and effecting a drop by drop delivery of liquid from the nozzle into the auxiliary chamber.
